UNITED STATES PATENT OFFICE

2,173,638

PROCESS FOR MANUFACTURING TEXTILE AGENTS

Meindert Danius Rozenbroek, Delden, Twenthe, Overijssel, Netherlands

No Drawing. Application April 12, 1937. Serial No. 136,513. In the Netherlands February 27, 1935

7 Claims. (Cl. 260—400)

It has been proposed in British specification No. 409,598 and Dutch specification No. 36,289 to convert higher alcohols into the corresponding esters of acids derived from phosphorus and to

5 sulphonate the said esters whereby products are obtained which contain sulphur as well as phosphorus in organically bound form.

The invention has for its object a process for manufacturing textile agents, such as cleansing, wetting out, foaming, dispersing, equalizing and bleaching agents which comprises sulphonating a compound derived from a polyhydric alcohol by esterifying at least one hydroxy group of the same with an acid derived from phosphorus so 10 as to produce a primary ester of the said acid, and esterifying or etherifying at least one remaining hydroxy group of the alcohol with a fatty acid or a monohydric alcohol having at least 6 carbon atoms.

15 The invention also relates to textile agents consisting of or containing the compounds specified above.

The ethers or esters sulfonated according to the invention are represented by the following formulae

R being the alkyl group with at least 6 carbon atoms present in the fatty acid or the monohydric alcohol from which the esters or ethers with the polyhydric alcohol are derived.

40 In the formulae given above the acid used is phosphorous acid; however, similar compounds can be derived from other acids containing phosphorus, especially phosphoric acid.

45 The monohydric alcohol used may be saturated or unsaturated, elaidinised or not, and primary, secondary or tertiary. If desired the alcohol may contain other substituents, e. g. halogen atoms, acyl or other groups. They may be manufactured

50 artificially or they may be obtained from natural products, e. g. waxes. Cholesterol, isoocholesterol and similar alcohols of a more complicated nature which can be obtained from waxes are also suitable for the purpose.

55 The higher fatty acids may also be saturated

or unsaturated and elaidinised or not. They may contain one or more hydroxy groups or other substituents, e. g. halogen atoms, acyl or other groups.

As polyhydric alcohols besides the glycol and glycerol mentioned in the above formulae, erythritol, propene diol, 2,3 butanediol, the alcohols obtained by reduction of sugars etc., may be used. Instead of the polyhydric alcohols one can also use partial ethers of the polyhydric alcohols 5 which contain at least two free hydroxy groups, e. g. the polyglycol or polyglycerol ether. Aminoethers with at least two free hydroxy groups, e. g. triethanol amine, are also suitable.

The above described phosphorus containing 10 ethers or esters are then sulphonated according to methods known per se. The sulphonation can be carried out with sulphuric acid or other sulphonating agents, e. g. oleum, sulphuric acid anhydride or chlorsulphonic acid, alone or together 15 with water binding agents, e. g. phosphorus pentoxide. The sulphonating agent can be added to the material to be sulphonated or vice versa.

The compounds obtained according to the invention are distinguished from the substances obtained according to prior processes by the presence of a monoesterified phosphoric acid or phosphorous acid group, i. e. a group resulting if a polybasic acid of this character is esterified with one hydroxy group of an alcohol. The presence 20 of this monoesterified acid group has a favourable influence on the properties of the compounds obtained. So e. g. the clearness of a dilute solution in hard water after standing is better. The solutions in soft water are even absolutely 25 clear.

Not only the solubility but also the resistance 30 against moderately concentrated alkaline solutions, e. g. a sodium hydroxide solution of 15%, even at the boiling point, is improved.

40 Suitable starting materials are mixtures of fatty acids and fat alcohols as e. g. obtained by the saponification of waxes and by the incomplete reduction of fatty acids to alcohols. The fatty acid may e. g. be esterified and the alcohol 45 etherified both with glycol, and in the mixture obtained the ester and the ether may be converted into the corresponding monoesterified phosphorus compounds and finally the mixture may be sulphonated.

50 The sulphonated compounds obtained according to the invention can be converted into substances containing active oxygen by treating the non-neutralised sulphonation product with a peroxide and neutralising the reaction product, or 55

by reacting the neutralised product with a peroxide. The product thereby acquires bleaching properties.

The invention will be illustrated by the following examples:

Example I

20 parts by weight of the monostearyl ether of glycol in molten condition are poured into 11 10 parts by weight of PCl_3 and slowly heated for some time until the development of gas is substantially finished. After cooling, 20 parts by weight of sulphuric acid are slowly added to the reaction mixture, the mass being well stirred and 15 care being taken that the temperature generally does not exceed 35° C. The sulphonate is then freed from the excess of acid by washing with a mixture of water and Glaußer's salt and neutralised.

20

Example II

225 parts by weight of the monolaurylether of glycol are esterified with 150 parts by weight of 25 P_2O_5 and then sulphonated with ± 250 parts by weight of sulphuric acid at a moderately elevated temperature. The neutralised product is a very good wetting out agent.

25

I claim:

- 30 1. The process which comprises reacting a compound selected from the group consisting of (a) ethers made from a polyhydric alcohol and a high molecular weight aliphatic alcohol and (b) esters made from a polyhydric alcohol and a high molecular weight fatty acid, with an inorganic acid derived from phosphorus, and sulphonating the resultant inorganic acid ester.
- 35 2. The process which comprises reacting an ether made from a polyhydric alcohol and a high molecular weight aliphatic alcohol, with an in-

40

organic acid derived from phosphorus and sulphonating the resultant inorganic acid ester.

3. The process which comprises reacting an ester made from a polyhydric alcohol and a high molecular weight fatty acid, with an inorganic acid derived from phosphorus, and sulphonating the resultant inorganic acid ester.

4. The process which comprises reacting a mixture of (a) an ether made from a polyhydric alcohol and a high molecular weight aliphatic alcohol and (b) an ester made from a polyhydric alcohol and a high molecular weight fatty acid with an inorganic acid derived from phosphorus and sulphonating the resultant inorganic acid ester mixture, the said mixture of an ether made from a polyhydric alcohol and a high molecular weight aliphatic alcohol and an ester made from a polyhydric alcohol and a high molecular weight fatty acid being obtained from a pre-existing mixture of a high molecular weight aliphatic alcohol and a high molecular weight fatty acid by etherifying the said aliphatic alcohol and esterifying the said fatty acid in the mixture with a polyhydric alcohol.

5. Sulfonated esters made from a compound selected from the group consisting of (a) ethers made from a polyhydric alcohol and a high molecular weight aliphatic alcohol and (b) esters made from a polyhydric alcohol and a high molecular weight fatty acid, and an inorganic acid derived from phosphorus.

6. Sulfonated esters made from an ether of a polyhydric alcohol and a high molecular weight aliphatic alcohol, and an inorganic acid derived from phosphorus.

7. Sulfonated esters made from an ester of a polyhydric alcohol and a high molecular weight fatty acid, and an inorganic acid derived from phosphorus.

MEINDERT DANIUS ROZENBROEK.

40

CERTIFICATE OF CORRECTION.

Patent No. 2,173,638.

September 19, 1939.

MEINDERT DANIUS ROZENBROEK.

It is hereby certified that the above numbered patent was erroneously issued to the inventor, said "Rozenbroek" as owner of the entire interest therein, whereas said patent should have been issued to Meindert Danius Rozenbroek, of Delden, Twenthe, Overijssel, Netherlands, assignor, by direct and mesne assignments, to himself and N. V. Chemische Fabriek Servo, a Limited Liability Company, of Delden, Twente, Overijssel, Netherlands, a corporation of the Netherlands, as shown by the record of assignments in this office; and that the said Letters Patent should be read with this correction therein that the same may conform to the record of the case in the Patent Office.

Signed and sealed this 2nd day of January, A. D. 1940.

(Seal)

Henry Van Arsdale,

Acting Commissioner of Patents.
